UNITED STATES PATENT OFFICE

1,938,518

GAS PRODUCER FUEL SUPPORT

Paul Achille Joseph Cousin, Loos les Lille,
France, assignor to Etablissements Ernest
Arnoult, Société Anonyme, Paris, France

Application October 23, 1928, Serial No. 314,503,
and in France November 5, 1927

1 Claim. (Cl. 48—66)

The present invention relates to improvements in gas producers having an ash pit provided with a water seal and adapted for manual or mechanical cleaning and it has for its object a gas producer of this class which will be of a simplified construction and will have an improved efficiency.

The gas producer fuel support in accordance with the invention comprises a water chamber disposed below the grate, an air blast device having submerged orifices being located within said chamber, said fuel support having orifices for the exit of the mixture of air, steam and emulsified water which is forced through the gas producer.

Further characteristics of the invention will be specified in the following description, with reference to the appended drawings, which are given by way of example.

Fig. 1 is a vertical sectional view of a gas producer with revolving fuel support for mechanical cleaning provided with the improvements according to the invention.

Fig. 2 is a view similar to Fig. 1 showing a modification.

Fig. 3 is a partial sectional view, on a larger scale, of the water inlet shown in Fig. 1 or 3.

Fig. 4 is a vertical sectional view of another modification.

In Figs. 1, 2 and 4, A is the lower portion of the gas producer body, and a is an air blast admission of a known type, comprising a central tube d supplying air below a hollow cap e; tube d is secured to the device formed by the grate b and the sole plate c of the ash pan, and its axis coincides with the axis of the gas producer. Said tube is extended below the sole plate c of the ash pan by an air supply tube f, provided with a water seal g. The sole plate c of the ash pit may be flat or may have the shape of a surface of revolution.

In the present example, the space between the blower a, the grate b and the sole plate c of the ash pan forms a water chamber p which is thus situated below the grate. The upper part of the tube d is above the water level in chamber p, whilst the lower edge m of the hollow cap e is immersed in the water of chamber p, thus forming submerged air inlets h along the whole periphery of cap e. The grate b is provided with outlet apertures n above the level of the water in the ash-pan.

Water is supplied to chamber p from the ash pan, through orifices q (Figs. 1 and 4) formed in the walls of grate b at a level below the water

level in the ash pit. The orifices q are covered by small caps i having downwardly directed orifices r (Fig. 4) so disposed as to remain unobstructed notwithstanding the movements of the grate during the cleaning step.

Fig. 1 also illustrates a cleaning arrangement comprising an opening s adapted to allow the insertion of the arm, and normally closed by a plate t and an oppositely disposed plate w.

Fig. 2 shows the same arrangement with another form of grate.

Fig. 4 shows a modification of the arrangement for the supply of water to chamber p; the water is herein admitted into chamber p through pipes j; the ends of said pipe which open at the outside of chamber p are provided with strainers preventing the sludge formed by the finely-divided ash from clogging up said pipes. The said pipes j are provided at the lower part with an emptying plug k.

The operation of my improved gas producer is as follows:

Water chamber p is supplied with more or less hot water from the ash pan and said water is further heated at the expense of all the heat radiated from the grate. The air blast passes upwards through the tube d and downwards in the cap e, through the inlets h and through the body of hot water in chamber p and is moistened by entrained water particles, and the mixture or emulsion of air and water will impinge upon the upper walls of the grate b which are highly heated and act as vaporizing surfaces; the mixture flowing through the orifices n of the grate, instead of being an emulsified mixture of air and water, as before, is an emulsified mixture of air, steam and water. The steam already formed below the grate will be superheated and will cause the evaporation of the particles of water which have not yet been evaporated and are impelled by the current.

In the devices above described the water which is supplied to the water chamber beneath the grate is taken from the ash pit, but I may obviously provide a separate water supply. The gas producer may also be provided with a grate of the type shown in Fig. 1, but having submerged orifices as specified in my copending patent application No. 314,502, filed October 23, 1928.

The apparatus herein described offers numerous advantages and chiefly the following: I dispense with the use of a special boiler for the gas producer, or of special piping if a central steam plant is available; I also prevent the

110

formation of blowholes or channels which are due, in the usual gas producers with steam supply, to the irregular distribution of the ash or slag caused by the irregular and nonadjustable steam supply.

Further, the supply of the steam and air mixture is quite regular and this prevents the formation of compact masses of ash or slag which prevents the passage of air, so that I obtain a regular gas production in all parts of the producer body and a more improved disintegration of the slag. The loss of heat due to radiation and to the presence of unconsumed material and finely-divided particles is also much reduced. It has been ascertained by experiments that the chemical composition of the producer gas is improved, that the output is made perfectly uniform, that the calorific value of the gas is increased, and that the amount of undecomposed steam is a minimum; furthermore, a single adjustment of the operation is required.

Obviously, the said invention is not limited to the details of construction herein described and represented, which are given solely by way of example.

Having now described by invention what I claim as new and desire to secure by Letters Patent is:

A gas producer fuel support comprising a water sealed ash-pan, a closed hollow grate structure in said ash-pan provided with at least one aperture which is situated above the level of the water in the ash-pan and through which air and steam are adapted to pass from the interior of said grate into said fuel, at least one pipe opening at one end at the lower part of and within said grate and at the other end into said ash-pan, below the water level therein, and an air blast admission conduit opening in said hollow grate under the water level in said hollow grate.

PAUL ACHILLE JOSEPH COUSIN.
